(57) **CLAIM**

The ornamental design for a remote for a display and operating device, as shown and described.

DESCRIPTION

FIG. 1 is a front side perspective view of a remote for a display and operating device showing my new design; FIG. 2 is a rear side perspective view of the remote for a display and operating device of FIG. 1;

FIG. 3 is a left side elevational view of the remote for a display and operating device of FIG. 1;

FIG. 4 is a right side elevational view of the remote for a display and operating device of FIG. 1;

FIG. 5 is a front side elevational view of the remote for a display and operating device of FIG. 1;

FIG. 6 is a rear side elevational view of the remote for a display and operating device of FIG. 1; and,

FIG. 7 is a top side plan view of the remote for a display and operating device of FIG. 1.

The broken lines shown in the drawings illustrate portions of the remote for a display and operating device that form no part of the claimed design.
